UNITED STATES PATENT OFFICE.

HARRY G. TRAVER, OF BEAVER FALLS, PENNSYLVANIA.

DESIGN FOR A CAR FOR AEROPLANE SWINGS.

Application filed April 21, 1925. Serial No. 13,179. Term of patent 14 years.

To all whom it may concern:

Be it known that I, HARRY G. TRAVER, a citizen of the United States of America, residing at Beaver Falls, in the county of Beaver and State of Pennsylvania, have invented an original and ornamental Design for a Car for Aeroplane Swings, of which the following is a specification, reference being had to the accompanying drawing, forming part thereof, in which—

Figure 1 is a perspective view looking at the front and one side of the car; and
Figure 2 is a perspective view looking at the front, bottom and side opposite to that shown in Figure 1.

I claim:

The ornamental design for a car for aeroplane swings, as shown.

HARRY G. TRAVER.
